CLAIM

The ornamental design for a compressed air operated flashlight, as shown and described.

DESCRIPTION

FIG. 1 is a front perspective view of the compressed air operated flashlight embodying this invention;
FIG. 2 is a rear perspective view of said compressed air operated flashlight;

FIG. 3 is a reduced front elevational view of FIG. 1;
FIG. 4 is a right side elevational view of FIG. 1;
FIG. 5 is a top plan view of FIG. 1;
FIG. 6 is a right side elevational view of FIG. 1;
FIG. 7 is a rear elevational view of FIG. 1; and,
FIG. 8 is a bottom plan view of FIG. 1.
